UNITED STATES PATENT OFFICE.

FRANKLIN G. PALMER, OF PHILADELPHIA, PENNSYLVANIA.

VAPOR-STOVE.

SPECIFICATION forming part of Letters Patent No. 563,982, dated July 14, 1896.

Application filed November 6, 1890. Serial No. 370,460. (No model.)

To all whom it may concern:

Be it known that I, FRANKLIN G. PALMER, a citizen of the United States, residing in the city and county of Philadelphia, in the State 5 of Pennsylvania, have invented certain new and useful Improvements in Vapor Stoves, of which the following is a specification.

My invention relates generally to stoves in which oil is employed as the fuel and led from 10 a reservoir to a burner where it is transformed into burning vapor.

It is the object of my invention to form an oil stove in such manner, and to provide in connection with it such a torch and such 15 torch-saturating devices as will permit of the stove's being put in operation with readiness and certainty. Further objects are the provision of a simple and effective valve to control the supply of oil to the stove,—and of a 20 device for guiding the torch to the stove burner and for retaining said torch in position to occasion the heating and ignition of the oil supplied to said burner.

In the drawings, 25 Figure 1 is a view in perspective of a stove embodying my invention.

Figure 2 is a detail view in side elevation of the burner pipe, its valve, the burner, and the torch guide.

30 Figure 3 is a plan view partly sectional of a portion of the burner pipe, its valve, the torch receiver and the torch guide.

Figure 4 is a view similar to Figure 2 illustrating however a modified form of torch 35 guide.

Figure 5 is an elevational view of the devices shown in Figure 4, sight being taken from the right hand side of said Figure 4, and the valve operating head L^2 being supposed 40 removed.

Figure 6 is a central vertical sectional elevation through the torch holder.

45 Figure 7 is a longitudinal sectional elevation through the cap of the torch, and illustrating the application to said cap of the rod and its nut, and the asbestos packing.

Figure 8 is a sectional plan view of a modified form of valve for the burner pipe.

50 Figure 9 is a detail view of the head of the valve shown in Figure 3.

Figure 10 is a view of a torch receiver em-

bodying a side pocket, and equipped with an outlet pipe.

Similar letters of reference indicate corresponding parts.

In the drawings, A is the frame work of the stove, being, as such, of any preferred character,—that shown consisting of a flat top a supported upon standards a^x . This top embodies the usual grated opening a' , beneath 60 which is situated the burner, described hereinafter.

B is a permanent oil reservoir, being a holder of any preferred construction, which is supported, as is customary in stoves of this 65 character, in a position above or distant from the stove proper so as to avoid undue heating of its contents, and also so as to occasion the feeding of its contents to the stove by gravity.

F is a pipe the central portion of which is 70 supported upon the standards of the stove. One end portion, F^x , of this pipe is carried upward from the stove, and upon its extremity is mounted the reservoir B hereinbefore described. This end portion F^x serves 75 not only to support the reservoir, but also, by being in communication with its interior, serves as the channel through which its contents gravitate to the stove. The other end portion, F' , of the pipe F is also carried upward, preferably from another part of the stove, and upon its extremity is mounted a torch holder, G, being a container of shape 80 suitable to receive the torch employed, and in communication with the pipe.

It will now be understood that oil deposited in the reservoir B will normally, by reason of the communication established through the pipe F, exist upon the same level in both the reservoir and the torch holder.

The torch-holder G is preferably supported in such position that its bottom occupies a level slightly lower than that of the reservoir B, but the end of the pipe member F' opens through the side of said holder G forming a 95 port opening at a point above its bottom and about on a level with the bottom of the reservoir B,—with the result that a pocket is formed in the bottom of said holder. It will therefore be apparent that when the oil 100 reaches the level of the bottom of the reservoir B and the open end of the pipe end F' ,

it will, in the further operation of the stove, cease to run out of the holder G, and in consequence the oil contained therein below the level of the end of the pipe member F will 5 be retained for the uninterrupted saturation of the torch.

H is the burner supply pipe, which is in communication with the pipe F. This pipe H from the point where it taps or is joined 10 to said pipe F leads at some radial distance from the burner, upward almost to the grate, where it bends abruptly and returns downward, in such manner that it does not cross the burner, both members of the elbow or 15 return bend h³ being so formed as to be upon the same side of the burner. The lower end of the downwardly bent pipe is at the proper level horizontally extended to the discharge nozzle, but preferably embodies in its horizontal extension h^x, an elbow, h', in connection with which elbow is also formed a boss h².

I is the discharge nozzle or burner, being a short vertical tube formed upon the extremity of the pipe H, and constituting a 25 continuation of the same. The lower end of this nozzle depends below the burner pipe. J is a pan or receiver, surrounding and connected with the lower portion of the burner I. In the ordinary form of vapor stove this pan 30 is employed to contain a small quantity of oil, which when it is desired to put the stove in operation, is ignited and heats the burner and discharge nozzle, so that when the oil is turned on the latter is by contact with such 35 heated parts and by the heat from the flame, vaporized, and the vapor set on fire. When the ordinary form of pan is used, however, it sometimes happens that when the parts of the burner become heated, large flames shoot 40 up through the centre of the burner, accompanied by slight explosions. To obviate this I have devised the plan of forming in the margin of the pan a deep pocket j, as shown in Figure 10, which receives a great part of 45 any oil placed in the pan, with the result that in operation the oil in the main body of the pan is first consumed, and by the time the parts of the burner become heated only the oil contained in said pocket remains, and 50 said pocket, being radially separated from the burner, the flame rising from the oil which it contains is at such distance from the burner as to avoid the creation of the large flames mentioned.

55 J^x, Figure 10, is an outlet pipe leading from the pan, at a point near the upper edge of the latter, to a reservoir or receptacle of any suitable character.

Stoves of this character are sometimes inadvertently extinguished without their flow of oil being stopped, and said pipe J^x is provided for the purpose of collecting the oil which continues to flow after such extinguishment and conducting it to a place of 65 storage.

K is a vertical stem, depending from the lower end of the burner, provided with an

operating head K', and intended to operate a burner-cleaning needle which works within the nozzle I in the manner usual in stoves of 70 this character.

In connection with the burner supply pipe, I apply at the elbow and boss in the horizontal portion thereof a key or valve of a novel construction. The boss h² referred to 75 has a screw-threaded exterior, as shown in Figure 2, and is interiorly bored out to form a cylindrical seat the inner end of which is conical and opens into the bore of the burner pipe H. L is a key, the enlarged head l of 80 which is shaped to accurately fit said seat. L^x is a cap, embodying an aperture fitted to the stem or shank of the key, and being screw threaded to engage with the exterior thread of the boss. This cap is adapted 85 when screwed upon said boss to bear against the rear portion of the head of the key so as to maintain it firmly, but free for rotation, within its seat. The advance end of the head will, when said head is forced home to 90 its seat, extend into and across the bore of the burner pipe. L' is a channel cut through the substance of the advance end of said key, so that, when the key is in a given position, the channel registers with the bore of 95 the burner pipe and permits the passage of its contents,—but when said key is rotated away from such position, the substance of the key closes said bore and shuts off the supply of the oil to the flame. The outer end 100 of the key stem is provided with a head L² for convenience of manipulation.

In Figure 8 I illustrate a slightly modified form of this valve. In said figure a bore, circular in transverse section, extends downward through the substance of a slight enlargement at the elbow h', the circumference of which (bore) reaches to the inner side of the channel of the pipe h^x. M is a plug adapted to fit within said bore, and provided 110 with a groove or channel m which by the rotation of the plug may be thrown into or out of registry with the channel of the pipe. This plug is equipped with a handle M^x, which passes through a slot m' in the said 115 enlargement, elongated to permit of the throw of said handle, to open or close the passage of the pipe.

To the upper end of the return bend h³ is, in any preferred manner, secured a bracket 120 or arm which supports in position over the nozzle of the oil pipe a flame tube N and radiator O of the usual construction.

The burner pipe with its elbow and bends, as will be apparent, exists in this construction, at one side of the flame of the stove, thus leaving an unobstructed approach to the other side of the flame.

P is what I term a torch guide, the same being, as shown in the construction represented in Figures 1, 2, and 3, a tube which may be fashioned in any convenient manner, and which is conveniently supported in the frame-work of the stove. The guide is pref-

erably supported in an inclined position within the open space at one side of the flame which this construction of stove provides, as described,—and as to its inner end 5 terminates just over the receiver J, when such receiver is employed, while its outwardly and upwardly extending body terminates conveniently just outside of the frame-work of the stove.

10 As an equivalent of this construction the arrangement represented in Figures 4 and 5 may be resorted to, in which in the stead of said inclined tube P, is employed a shelf Q, which, similarly, leads to the receiver, if a 15 receiver is employed, and similarly terminates outside of the frame-work of the stove. The shelf is preferably formed of sheet metal, and both of its edges are upturned, that nearest the burner, q, being but slightly upturned, 20 and that farthest from the burner, q', being upturned to a much greater extent. The object of turning up the edges of the shelf is to furnish a guide for the insertion of the torch and to keep the wind away from it.

25 R is the torch, the same being preferably constructed as shown in detail in Figure 9 of the drawings, in which r is a handle rod, one end of which is screw threaded,—and r² is a cylindrical cap, one end of which is constructed to form a neck which is threaded to screw upon said rod. r' is a mass of fibrous asbestos or other suitable material packed within so as to fill said cap and to surround the contained end of the rod r,—while r² is a retaining nut screwed upon the end of said rod and serving to retain said asbestos in position.

30 The torch is ordinarily stored in the torch holder G hereinbefore described, in which it is kept constantly saturated with the oil therein so as to become very inflammable. 40 When it is desired to start a fire in the stove, the torch is withdrawn from its holder, is ignited by a match or otherwise, and is inserted in the torch guide or holder in proper position for its flame to vaporize the contents of the pan or receiver and eventually ignite the flow from the discharge nozzle. The torch when placed within or upon the torch guide

and pan, or upon the torch guide alone, is left in such position, and maintained by the torch 50 guide until it effects the desired ignition.

When the torch guide formed as a shelf is employed, the upturned edge q should be cut away in the neighborhood of the burner so that it will not interfere with the contact of 55 the torch with the said burner.

Having thus described my invention, I claim—

1. In an oil or vapor stove, in combination, a burner, an oil reservoir, and a torch holder, 60 said oil reservoir and torch holder being in communication with the burner and with each other, substantially as set forth.

2. In an oil or vapor stove, in combination, a burner, and an oil reservoir and a torch 65 holder in communication with said burner and with each other, the torch holder being a receptacle adapted to contain oil and a torch and its communication with the reservoir and burner being established through an opening 70 formed in its side, substantially as set forth.

3. In an oil or vapor stove, in combination, a burner, an oil reservoir embodying an opening in its bottom, a torch holder the bottom of which occupies a lower level than the bottom of the reservoir, and which holder embodies in its side an opening at approximately the level of the bottom of the reservoir, and a pipe connection between the burner and the openings of the reservoir and torch holder, 75 substantially as set forth.

4. In combination with a vapor stove having a self generating burner in its central portion, a torch guide extending from the exterior of the stove to a point in the vicinity of 85 said burner, and adapted to guide a torch to said burner and to support said torch in such position that its flame will heat said burner.

In testimony that I claim the foregoing as my invention I have hereunto signed my name 90 this 13th day of October, A. D. 1890.

FRANKLIN G. PALMER.

In the presence of—
JOHN R. NOLAN,
F. NORMAN DIXON.
